UNITED STATES PATENT OFFICE.

WILLIAM J. BAUER, OF SYRACUSE, NEW YORK.

ANCHOR.

Application filed June 14, 1926. Serial No. 115,739.

This invention relates to an anchor of the folding fluke type in which means is provided for holding the flukes in their folded and unfolded positions.

One of the objects is to pivot the flukes to the supporting stem to swing in planes at substantially right angles to each other so as to cover a relatively wide area of the water bed or other anchorage and at the same time 10 to assure the grappling engagement of at least two of the wings at a time with said bed.

Another object is to make the flukes concavo-convex longitudinally and to limit their 15 opening movement in such manner that when unfolded to their extreme limits they will lie in the arcs of a spherical segment with their convex faces at the bottom so as to afford a more or less dish shaped grappling element.

A further object is to taper the heels of the flukes in such manner that contiguous sides of the tapers of adjacent flukes may 20 form cooperative stops for limiting the opening movement of the flukes.

A further object is to provide the supporting stem and locking collar with cooperative cam faces whereby the flukes may be held in their folded and unfolded positions 25 by a simple turning movement of the collar relatively to the stem.

Other objects and uses relating to specific parts of the device will be brought out in the following description.

In the drawings:

Figure 1 is a side elevation of an anchor embodying the features of my invention, the flukes being shown as locked in their closed or folded positions.

40 Figure 2 is a longitudinal sectional view of the same device taken on line 2—2, Figure 1.

Figure 3 is a horizontal sectional view taken on line 3—3, Figure 1, except that the flukes are locked in their open positions.

45 Figure 4 is a transverse sectional view taken on line 4—4, Figure 1.

Figure 5 is an inverted plan of a central portion of the device showing the flukes unfolded and the tapered inner ends engaged with each other for limiting the opening movement thereof.

50 Figure 6 is a sectional view on line 6—6, Figure 1.

55 As illustrated, this anchor comprises a

main supporting stem —1—, a plurality of, in this instance four, folding flukes —2— and a locking collar —3— slidably lengthwise of and upon the stem —1— to cooperate with said stem for holding the flukes in 60 their folded and unfolded positions.

The lower end of the stem —1— is provided with a substantially flat lower face —4— and a plurality of, in this instance four, outwardly projecting apertured lugs —5— arranged in uniformly spaced relation circumferentially and, therefore, at substantially right angles to each other for receiving and supporting the inner ends of the 65 flukes —2—.

The upper end of the stem is provided with an eye —6— for receiving one end of a rope, chain or other suitable cable having its other end attached to the boat or other float in any well-known manner for producing 70 the desired connection between the float and anchor.

The major portion of the length of the stem —1— between the lugs —5— and eye —6— is substantially straight but preferably corrugated transversely for strength, the corrugations consisting of a plurality of, in this instance four, lengthwise ribs —6'— and —6'— arranged in uniformly spaced relation about the axis of the stem and preferably in vertical alignment with the lugs —5—, said ribs being preferably of uniform radial width throughout the major portions of their lengths to permit the collar —3— to slide and turn freely thereon 75 when adjusting it from one extreme to its other extreme locking position.

The lower ends of two of the diametricaly opposite ribs —6'— are slightly enlarged or widened to form shoulders —8— which are arranged in axially spaced relation to the corresponding lugs —5— to form recesses —9—, said shoulders being adapted to be engaged by the cam faces of the collar —3— for holding the flukes —2— in their 80 open or unfolded positions in a manner presently described.

The upper portions of two of the diametricaly opposite ribs —6'— are also enlarged or widened to form shoulders —10— in axially spaced relation to the shoulders —8— a distance slightly greater than the distance between the pivots of the flukes —2— and free ends of the flukes and adapted to be engaged by the cam face of 100 105 110

the collar —3— for locking the flukes in their closed or folded positions as shown in Figures 1 and 2.

The upper ends of the ribs —6'— and 5 —6'— are connected by an annular bearing —11— just below the shoulders —10— and against which the free ends of the flukes are adapted to rest when locked in their folded positions.

- 10 The flukes —2— are concavo-convex longitudinally from end to end and are arranged in uniformly spaced relation circumferentially about the axis of the stem —1— in alinement with their respective 15 lugs —5—, the opposite longitudinal edges of each fluke being substantially straight and parallel throughout the major portion of its length.

Each fluke is provided near its lower or 20 inner end with a pair of inwardly or upwardly projecting lugs —12— in transversely spaced relation corresponding to the thickness of the lugs —5— so as to engage opposite faces thereof and to which they are 25 pivoted by pivotal bolts —13—.

The lower or inner end of each fluke —2— is tapered or beveled at —14— at an angle of substantially 45 degrees to its longitudinal center and projects downwardly or inwardly beyond their pivots —13— a distance corresponding approximately to the distance between said pivots and the axis of the stem —1— so that when the flukes are unfolded to the position shown by dotted 30 lines in Figure 2 and by full lines in Figure 3, the contiguous beveled edges of adjacent flukes will abut against each other below the lower end of the stem —1— as shown in Figure 5 to limit their opening or unfolding 35 movements in such manner that the flukes will lie in the arcs of a spherical segment as shown by dotted lines in Figure 2.

Under these conditions the lower surfaces of the flukes across the lower end of the 45 stem will be substantially smooth and continuous permitting the entire weight of the anchor to be thrown upon the points of two or more of the flukes when dragged upon the water bed or through other obstructions during which operation the two engaging flukes will have a side draft from the points toward the center with the transversely flat inner faces presented their full widths at an angle to the bed for greater resistance to draft 55 when anchored in said bed.

The collar —3— is preferably made in the form of an inverted cup or concavo-convex in cross section and is provided with a central opening —15— and diametrically opposite grooves —16— leading laterally from the central opening which is of sufficient diameter to permit the collar to slide freely along the main body of the stem —1— but is of less diameter than the width of the 50 stem across the shoulders —8— and —10—.

except at the grooves —16— which are slightly wider than the shoulders —8— and —10— to permit the collar to pass over said shoulders when the grooves or recesses —16— are alined therewith.

On the other hand, when the collar is turned so as to bring the groove —16— out of registration with the shoulders —8— and —10— the latter will serve to retain the collar against axial displacement from the 75 stem, it being understood that the outer diameter of the eye —6'— is sufficiently small to permit the collar to be removed from the upper end of the stem when the recesses —16— are registered with the shoulders 80 —8— and —10—.

The upper end of the collar —3— is provided with an annular flange having end cam faces —17— between the grooves —16— to engage the shoulders —8— and —10— 85 for locking the flukes —2— in their open or unfolded positions as shown in Figure 3 or in their folded positions as shown in Figure 2.

Operation.

90

For example, when the flukes are folded with their free ends resting against the annular bearing —11— as shown in Figures 1 and 2, the collar —3— is moved downwardly 95 to surround the upper ends of the flukes after which the collar may be turned slightly in the proper direction to cause its cam faces —17— to engage the shoulders —10— and thereby to lock the collar against the upper 100 ends of the folded flukes for holding the latter in their closed positions.

The turning of the collar in a reverse direction to register its groove —16— with the shoulders —10— permits said collar to 105 be raised sufficiently to release the flukes whereupon the latter drop by their own weight until the contiguous beveled edges of their inner ends engage each other whereupon the collar may be moved downwardly 110 along the stem —1— so that its upper end registers with the recesses —9— and then by turning the collar in the proper direction will bring its cam faces —17— into engagement with the shoulders —8— while the 115 lower marginal flanges of the collar will rest against the adjacent portions of the upper faces of the flukes to hold said flukes in their open positions following which the anchor is ready for use.

It will be observed that the outer ends of the folding flukes are also tapered to form digging points and thereby to facilitate the entrance of the flukes into the water bed.

It will also be noted that the collar —3— is provided with laterally projecting wings or finger pieces to facilitate the turning of the collar about the axis of the stem.

The downwardly flaring walls of the col- 130

120

125

130

lar provide an annular marginal bearing flange of relatively large diameter to engage the unfolded flukes corresponding distances from the axis of the stem to more effectively hold the flukes in their unfolded positions while on the other hand when the flukes are folded the concave inner walls of the collar serve to cap or overlie the free ends of the flukes to hold them in close contact with the periphery of the annular bearing —11—, the upper shoulders —10— being spaced above the pivots —13— a distance slightly greater than the distance between the pivots and free ends of the flukes so as to allow the upper annular flange of the collar —3— to pass between said shoulders and free ends of the flukes as shown in Figure 2 for firmly holding said flukes in their folded positions, the flare of the collar being approximately the same as the flare of the adjacent ends of the folded flukes.

What I claim is:—

1. An anchor comprising a stem having means at one end for attachment to a cable, flukes arranged in uniformly spaced relation circumferentially around the axis of the stem and having one end pivoted to the other end of the stem to fold toward and from the stem, said pivoted ends being provided with tapered extensions abutting against each other across the lower end faces of the stem when the flukes are unfolded.

2. An anchor comprising a stem, flukes pivoted to the lower end of the stem to fold and unfold toward and from said stem, means for limiting the opening movement of

the flukes, a collar slidable endwise of and upon the stem for engaging the upper faces of the flukes when unfolded and for engaging the free ends of the flukes when folded, said collar being turnable about the axis of the stem and provided with a cam, a shoulder on the stem adapted to be engaged by the cam when the collar is turned in one direction for locking the flukes in their open positions and an additional shoulder on the stem adapted to be engaged by the cam when the collar is turned in one direction for locking the flukes in their closed positions.

3. An anchor comprising a stem having means at one end for attachment to a cable, flukes pivoted to the other end of the stem in uniformly spaced relation circumferentially about the axis of the stem at right angles to each other to fold and unfold toward and from the stem, said flukes having tapered inner ends extending beyond their pivots to project partially across the lower end face of the stem when unfolded, a collar slidable lengthwise of and upon the stem for engaging and holding the flukes in their folded and unfolded positions and turnable about the axis of the stem, said collar and stem being provided with cooperative means effective by the turning movement of the collar in one direction for holding said collar against upward displacement when in holding engagement with the flukes in either the folded or unfolded positions.

In witness whereof I have hereunto set my hand this 26th day of May 1926.

WILLIAM J. BAUER.
